US00D551895S

(12) **United States Design Patent** (10) **Patent No.:** **US D551,895 S**
Allen et al. (45) **Date of Patent:** **** Oct. 2, 2007**

(54) **CONTAINER**

(75) Inventors: **Monty L. Allen**, Dallas, GA (US);
Kenneth C. Kreatle, Atlanta, GA (US);
Leon J. Scott, III, Atlanta, GA (US)

(73) Assignee: **In Zone, Inc.**, Austell, GA (US)

(**) Term: **14 Years**

(21) Appl. No.: **29/231,675**

(22) Filed: **Jun. 8, 2005**

(51) **LOC (8) Cl.** **07-01**

(52) **U.S. Cl.** **D7/313; D7/300; D34/39**

(58) **Field of Classification Search** ..... **D7/300, D7/313, 312, 306, 606, 605, 131, 146.6, 144.5, D7/469; D34/39; D9/633, 773, 527; D23/205, 222/146.6, 131, 400.7, 144.5, 469; 137/212, 137/322; 217/76; 220/592.19, 4.04, DIG. 1**

(57) **CLAIM**

The ornamental design for a container, as shown and described.

DESCRIPTION

FIG. 1 is a perspective view of a container showing a new design.

FIG. 2 is a front elevation view thereof.

FIG. 3 is a right side elevation view thereof, the left side being a mirror image thereof.

FIG. 4 is a back elevation view thereof.

FIG. 5 is a top plan view thereof; and,

FIG. 6 is a bottom plan view thereof.

The broken line in FIG. 6 represents an unclaimed boundary of the design.

1 Claim, 3 Drawing Sheets
